(57) **CLAIM**

The ornamental design for a support base for a dispenser, as shown and described.

DESCRIPTION

FIG. 1 is a front perspective view of a support base for a dispenser;

FIG. 2 is a front view of the support base for a dispenser illustrated in FIG. 1;

FIG. 3 is a rear view of the support base for a dispenser illustrated in FIG. 1;

FIG. 4 is a left side view of the support base for a dispenser illustrated in FIG. 1;

FIG. 5 is a right side view of the support base for a dispenser illustrated in FIG. 1;

FIG. 6 is a top view of the support base for a dispenser illustrated in FIG. 1;

FIG. 7 is a bottom view of the support base for a dispenser illustrated in FIG. 1; and,

FIG. 8 is a front perspective view of the support base for a dispenser illustrated in FIG. 1, shown in use with a dispenser disposed thereon.

The broken lines in the figures show disclaimed portions of the support base for a dispenser and form no part of the claimed design. The thin solid lines illustrate surface contour and form no part of the claimed design.

1 Claim, 8 Drawing Sheets
